(57) **CLAIM**

The ornamental design for a drain pipe, as shown and described.

DESCRIPTION

FIG. 1 is a perspective view of a drain pipe showing the claimed design;

FIG. 2 is an exploded view of the perspective view showed in FIG. 1;

FIG. 3 is another perspective view of a drain pipe showing the claimed design;

FIG. 4 is an exploded view of the perspective view showed in FIG. 3;

FIG. 5 is a front elevational view thereof;

FIG. 6 is a rear elevational view thereof;

FIG. 7 is a left side view thereof.

FIG. 8 is a right side view thereof.

FIG. 9 is a top plan view thereof; and,

FIG. 10 is a bottom plan view thereof.

The broken lines depict portions of the drain pipe that form no part of the claimed design.
